FINGER BOARD

Lantrip M. York, Lake Charles, La.

Application April 15, 1940, Serial No. 329,806

1 Claim. (Cl. 211—60)

My invention relates to improvements in finger boards for use on the boom of oil well rigs of the type forming the subject matter of my U. S. Letters Patent No. 2,168,837, dated August 8, 1938, the present invention being designed as an improvement over the finger board structure of said patent.

The primary object of my invention is to provide a finger board structure, whereby the racking of pulled sections of well tubing may be accomplished with greater speed and with a greater margin of safety than with the structure of said patent.

To the accomplishment of the above, and subordinate objects presently appearing, the preferred embodiment of my invention has been illustrated in the accompanying drawings, set forth in detail in the succeeding description, and defined in the claim appended hereto.

In said drawings:

Figure 1 is a fragmentary view in side elevation of the preferred embodiment of my invention.

Figure 2 is a similar view in front elevation,
Figure 3 is a fragmentary view in side elevation,
Figure 4 is a view in top plan with parts shown
in section, and

Figure 5 is a view in vertical transverse section taken on the line 5--5 of Figure 4.

Referring to the drawings by numerals, the boom to which my improved finger board is designed to be applied being described in detail in my aforesaid patent, to which attention is directed, need not be entered into in detail herein. Suffice it to explain that said boom, designated 1, is a skeleton sectional structure, each section comprising four tubular longitudinal side members 2 connected together in front and rear pairs by cross braces 3 and diagonal struts 4, the sections being connected together end to end by tubular sockets 5 coupling the ends of the side members of adjoining sections together. The upper end of the boom 1 has suitably secured thereto, to project forwardly therefrom, a yoke 6 in which is mounted the usual sheave assembly 7 for the block and tackle including a hoisting cable 8 and a block 9 carried in the bight of said cable. Suitable guy wires, or cables, 10, are attached to the upper end of the boom 1 to hold the same in a position inclined slightly forwardly from the vertical. The elements 11, 12, and 13, form parts of brace means for the boom which need merely be identified in passing. The element 14 is an idler pulley for the cable 8, as will be understood.

The finger board, designated 15, has the form of a balcony-like skeleton structure, projecting forwardly and laterally of the boom 1 and including side pairs of parallel, upper and lower, tubular rails 16, 17, upon opposite sides of the boom, respectively, and extending forwardly thereof, each pair of rails being connected together at the ends thereof by tubular front and rear uprights 18, 19; a pair of parallel, upper and lower, front tubular rails 20, 21, extending between the upper and lower ends of said uprights 18, with tubular uprights 22 connecting the same together; rear pairs of upper and lower tubular side rails 23, 24, forming rear end extensions of the side pairs and inclining therefrom to the rear pair of longitudinal members 2 of one boom section; and a rear tubular, lower rail 25 extending across the front of the front pair of members 2 of said section and between the rear ends of the lower rails 17 of the described side pairs of rails, said rail 25 being secured at its ends to said rails 17. The upper and lower rails 16, 17, of said side pairs may be made in sections secured together by sleeve couplings 26 and pins 27 for convenience in assembling the structure. Also said upper and lower rails 16, 17 may be braced by tubular uprights 28 extending therebetween at suitable points.

The rear ends of the rails 23, 24, are detachably secured to the rear pair of longitudinal members 2 of boom 1 by suitable clamps 28 and bolts 30, and the lower rail 25 to the front pair of longitudinal members 2 by similar clamps 31 and bolts 32.

A pair of triangular platforms 33 extend between the lower rail 25 and the lower rear side rails 24, upon opposite sides of the boom, respectively.

A rectangular platform 34 of substantially the width of the boom 1 extends forwardly for a short distance from the lower rear rail 25 with its rear edge suitably secured to said rail.

A narrow catwalk 35 extends from the lower rear rail 25 forwardly along the lower side rails 17 and laterally along the lower front rail 21, said walk comprising a pair of side sections 36 and a front section 37, the side sections 36 being bolted at the rear ends thereof to the rear lower rail 25, as at 38, and the front ends of said sections 36 together with the ends of front section 37 are suitably secured to angle plates 39 extending between each lower side rail 17 and lower front rail 21.

A diagonal strut 40 extends downwardly from the front end of the platform 34 to one of the

cross braces 3 of the boom 1 to which it is secured by a clamp 41 similar to clamps 28, 31.

Guy wires 42 extend from the front corners formed by the juncture of the side rails 16 and front rail 20 upwardly to the boom 1 to which they are suitably secured.

A plurality of racking fingers, or rods, 43 extend forwardly from the lower rear rail 25 intermediate each section 36 of catwalk 35 and the platform 34.

A series of similar racking fingers 44 extend inwardly from one lower rail 17 in front of the racking fingers 43, said fingers 44 projecting inwardly beyond the adjacent catwalk section 36 from beneath the same.

In the use of the described finger board, and as will be apparent, the platforms 33, 34, and the catwalk 35 are utilized by an operator to manipulate the cable 8 and block 9 from different angles to guide the tubing sections, not shown, being pulled, into the spaces between selected racking fingers 43, 44, it being of course, understood that said cable 8 is lowered and raised in the space between the catwalk 35 and the platform 34 and racking fingers 43, 44. Thus, a single operator may easily and quickly rack a number of tubing sections and without danger of falling, or permitting the sections to fall, the rails 20, 16 and 23 providing hand grips 30

available in any position assumed by the operator.

The foregoing will, it is believed, suffice to impart a clear understanding of my invention without further explanation.

Manifestly the invention, as described, is susceptible of modification without departing from the inventive concept and right is herein reserved to such modifications as fall within the scope of the subjoined claim.

Having described the invention, what I claim is:

A racking and finger board structure for attachment to a derrick boom comprising a rectangular skeleton frame including front, rear and end bars, respectively, an angle plate disposed between said front bar and each end bar, attaching means on said rear and end bars whereby said frame is adapted for attachment to one side of the boom to extend laterally therefrom at a right angle thereto, a series of racking fingers secured to and extending from one end bar inwardly of said frame, and a platform panel extending along said one end bar and supported by said rear bar and an angle plate for use by a workman to rack pipe between said fingers, said fingers underlying said platform panel and extending inwardly, beyond said panel to accommodate the pipe therebetween.

LANTRIP M. YORK.
